UNITED STATES PATENT OFFICE.

WILLIAM GENTRY SHELTON, OF NEW YORK, N. Y.

DISPLAY OR ADVERTISING DEVICE.

1,418,740.

Specification of Letters Patent. Patented June 6, 1922.

Application filed January 30, 1920. Serial No. 355,169.

To all whom it may concern:

Be it known that I, WILLIAM GENTRY SHELTON, a citizen of the United States of America, residing in the borough of Manhattan, city, county, and State of New York, have invented certain new and useful Improvements in Display or Advertising Devices, of which the following is a specification.

10 This invention relates to display or advertising devices, and aims to provide improvements therein.

The invention provides a device for producing a fountain, and combines therewith a 15 motor-drive pump, and also conveniently illuminating means, the parts being combined as a portable unit, adapted to be placed in a shallow basin of water. The fountain is supplied with water from the 20 basin, and the jets conveniently run back into the basin, so that a small quantity of water serves for running the fountain for any length of time. The invention further provides a simple, durable and easily manu- 25 factured device of the character described. Other features of improvement in the combination and in parts will be hereinafter set forth.

An embodiment of the invention is illus- 30 trated in the accompanying drawing.

In said drawing:—

Fig. 1 is a vertical sectional view of said embodiment; and

Fig. 2 is a horizontal sectional view on 35 the line II—II, Fig. 1.

In said drawings, numeral 1 designates a globe and 2 a base upon which said globe sets.

The base 2 conveniently comprises a marginal or rim portion 3 and a center portion 4. The rim portion 3 and the center portion 4 are conveniently connected by radial arms 5. Set screws 7, adapted to project over the rim 8 of the globe 1, may be provided for holding the globe in place upon the base 2.

In the rim portion 3 of the base 2 there is provided a conduit 9, adapted to conduct water or other liquid. At desired points 50 around the rim portion 3 of the base, there are provided a number of jet orifices 11, through which liquid from the conduit 9 is adapted to be projected in jets. These jet orifices 11 are conveniently inclined 55 slightly to the axis of the base, so that the jets fall inwardly upon the globe 1.

The center portion 4 is preferably made hollow, to constitute a casing for a pump, as indicated at 13, and one of the arms 5 is conveniently grooved or made hollow so 60 as to provide a channel 15 connecting the interior of the casing 13 with the conduit 9 in the rim 3 of the base.

An impeller 19, preferably of the rotary type, is provided in the pump casing 13, and 65 said impeller is preferably driven by an electric motor 21. A pair of conductors 23 serve for supplying the current to the motor. The center portion 4 is conveniently provided with a socket portion 22, in which a 70 projecting part of the casing of the motor or stud 21 is fitted, conveniently by means of screw threads.

On the top of the casing of the motor 21 there is preferably mounted a lamp socket 75 25 and an incandescent lamp 26.

A set screw 29 projecting through the base into the conduit 15 serves as a convenient valve or means for regulating the flow 80 of liquid to the conduit 9.

The pump casing 13, the conduit 9 and the conduit 15 are preferably formed as channels or recesses in the base, which are open at the bottom. To close the recesses and channels, a plate 31 is provided. This 85 plate fits flush against the under side of the base, and thereby closes the channels. An opening 32 in the center part of the plate provides an inlet to the pump casing 13. A cut-out portion 33 in the plate 31 allows 90 the conducting wires 23 to pass from the underside of the base to the motor.

In use, the base, with its attached parts is intended to be set within a shallow basin or pan containing water or other liquid. 95 Feet 35 are provided for slightly raising the bottom of the base from the bottom of the pan, so that the water is free to flow beneath the base, to the inlet 32 of the pump. The conductors 23 pass beneath the base, and 100 over the edge of the basin, and a rubber tube 37 may be slipped over the parts of the conductor which pass under the water.

Upon the current being admitted to the conductors 23, it starts the motor 21 and 105 illuminates the lamp 26. The motor turns the impeller 19, and water or other liquid is forced into the conduit 9, via the conduit 15, and issues through the orifices 11 in jets. The jet orifices being preferably inclined toward the axis of the base, the jets or streams of water fall onto the globe and 110

flow down said globe into the basin or pan into which the device is set. There is thereby produced a circulation of the water in the pan or basin into the pump, out through 5 the jet orifices and back again to the pan or basin. The height of the jets may be regulated by the valve or screw 29.

The plate 31 being separately formed and removable, admits of ready access to the interior of the casing and to the conduits or channels in the base.

The globe 1 is preferably transparent or translucent, so that the light from the lamp may pass through the globe and illuminate 15 the jets of water or other liquid.

The globe 1 serves to protect the motor and lamp from the jets of water, and is readily removable for providing access to the motor and lamp.

20 Moreover, the device is constituted by a minimum number of parts which are readily manufactured and readily assembled.

The inventive ideas herein set forth may receive other embodiments than those specifically illustrated and described.

What I claim is:—

1. A display or advertising device comprising a unitary base, a conduit comprised in the rim of and integral with said base 30 having jet orifices leading from said conduit and adapted to direct upward streams of liquid from said base, and a motor-actuated pump for pumping water into said conduit, said base being adapted to rest in a shallow basin, said base having a centrally located pump casing and a conduit leading from said pump casing to said first-named conduit.

2. A display or advertising device comprising a unitary base, said base comprising a rim portion, a center portion and radial arms connecting said rim and center portions, a conduit comprised in said rim portion having jet orifices leading from said 45 conduit and adapted to direct upward streams of liquid from said base, and a motor-actuated pump for pumping water into said conduit, said base being adapted to rest in a shallow basin and said pump being adapted to draw liquid from said basin.

3. A display or advertising device comprising a unitary base, said base comprising a rim portion, a center portion and radial arms connecting said rim and center portions, a conduit comprised in said rim portion having jet orifices leading from said 55 conduit and adapted to direct upward streams of liquid from said base and a motor-actuated pump for pumping water into said conduit, said base being adapted to rest in a shallow basin and said pump being adapted to draw liquid from said basin, said base having a centrally located pump casing

and one of said radial arms having a conduit leading from said pump casing to said first-named conduit.

4. A display or advertising device comprising a unitary base a groove around the rim of said base having jet orifices leading from said groove and adapted to direct upward streams of liquid from said base, and a motor-actuated pump for pumping water into said groove, said base being adapted to rest in a shallow basin and said pump being adapted to draw liquid from said basin, said base having a centrally located pump casing, a groove leading from said pump casing to said first-named groove, said pump-casing and grooves being formed in said base and being open at their under side, and a plate separable from the base for closing the under side of said groove.

5. A unit comprising a unitary base adapted to be set in a bowl of water, said base having a water conduit therein, jet orifices communicating with said conduit, and a pump and an electric motor, said base and motor having a stud and socket connection between them, said pump being adapted to draw water from a bowl or the like and force it into said conduit and out through said jet orifices.

6. A unit comprising a unitary base adapted to be set in a bowl of water, said base having a water conduit therein, jet orifices communicating with said conduit, and a pump and an electric motor, said base and motor having a stud and socket connection between them, said base comprising an annular portion in which said water conduit and jet orifices are formed, and a central portion having a pump casing therein, said pump being adapted to draw water from a bowl or the like and force it into said conduit and out through said jet orifices.

7. A unit comprising a unitary base adapted to be set in a bowl of water, said base having a water conduit therein, jet orifices communicating with said conduit, and a pump and an electric motor, said base and motor having a stud and socket connection between them, said base comprising an annular portion in which said water conduit and jet orifices are formed, and a central portion having a pump casing therein, radial arms connecting said annular and central portion, and one of said arms having a conduit connecting said pump casing and annular conduit, said pump being adapted to draw water from a bowl or the like and force it into said conduit and out through said jet orifices.

In witness whereof, I have hereunto signed my name.

WILLIAM GENTRY SHELTON.
